UNITED STATES PATENT OFFICE.

ERNEST S. OSTLER, OF CHICAGO, ILLINOIS, ASSIGNOR TO STROMBERG ELECTRIC COMPANY, OF CHICAGO, ILLINOIS, A CORPORATION OF MAINE.

NOISELESS CLOCK MECHANISM.

Application filed July 31, 1925. Serial No. 47,236.

My invention relates to noiseless clock mechanism.

One of the objects of my invention is to provide a simple and efficient noiseless clock mechanism controlled by an intermittently energizable electromagnet.

Further objects will appear from the description and claims.

In the drawings, in which an embodiment of my invention is shown—

Figure 1 is a side elevation of a noiseless intermittent movement mechanism which may be used in a secondary clock;

Fig. 2 is a section on the line 2—2 of Fig. 1;

Fig. 3 is a horizontal section on the line 3—3 of Fig. 1; and

Fig. 4 is a fragmentary view showing the position certain parts assume when the electromagnet is energized.

Referring to the drawings in detail, the construction shown comprises an intermittently energizable electromagnet 1, a three point armature 2 therefor, a shaft 3 on which the armature 2 is mounted, a gear 4 mounted on this shaft, a pinion 5 meshing with the gear 4, a shaft 6 on which the pinion 5 is mounted, a crank 7 mounted on the shaft 6, and a coil tension spring 8 secured to the crank 7. Only a part of the clock train is shown, as this forms no part of the invention. The part of the clock train shown comprises a worm wheel 9 mounted on the armature shaft 3 and a worm gear 10 meshing with this worm wheel.

The pitch diameter of the gear 4 is three times the pitch diameter of the pinion 5 meshing therewith so that the crank 7 will revolve three times for each revolution of the armature 2. The armature 2 is so positioned with respect to the poles 11 of the electromagnet 1 and the other parts are so designed that when the electromagnet is

energized the crank 7 will move from the 45 position shown in Fig. 1 to the position shown in Fig. 4, this movement being a little more than 180° and sufficient to move the crank past its dead center position with respect to the line of action of the spring 8. 50 When the magnet is deenergized, the spring completes the revolution of the crank 7 and completes the step of the armature of the electromagnet, bringing this armature into position ready for the next step. 55

What I claim as new and desire to secure by Letters Patent of the U. S. is:—

1. A step-by-step movement mechanism comprising an electromagnet, a revolute armature therefor rotated a partial step 60 when the magnet is energized, and means for completing said step comprising a revolute crank driven from said armature and a spring secured to said crank, said crank being rotated past the dead center of 65 the line of spring action when the magnet is energized and the revolution of the crank being completed by the spring when the magnet is deenergized.

2. A step-by-step mechanism comprising 70 an electromagnet, a revolute armature therefor rotated a partial step when the magnet is energized, and means for completing said step when the magnet is deenergized comprising a revolute member driven 75 from said armature and rotated more than 180° and less than 360° when the armature is energized and rotated the remainder of the 360° when the armature is deenergized, and speed change transmission between said 80 armature and revolute member whereby the rotatable armature is rotated only a fractional part of a complete revolution for each complete revolution of the revolute member. 85

In witness whereof, I have hereunto subscribed my name.

ERNEST S. OSTLER.
